Filed June 6, 1962, Ser. No. 70,436

Term of patent 14 years

(Cl. D16—2)

FIG. 1 is a perspective view of a cabinet, aquarium and animal cage unit for biology classrooms or the like embodying our new design.

FIG. 2 is a side elevational view thereof taken from the left thereof as shown in FIG. 1; and

FIG. 3 is a plan view thereof.

The rear, not shown, is substantially flat and unornamented.

The dominant features of the design are shown in full lines in the drawings.

We claim:

The ornamental design for a cabinet, aquarium and animal cage unit for biology classrooms or the like, as shown and described.
